His Attorney

UNITED STATES PATENT OFFICE.

ERNEST KORTEN, OF SUNBURY, PENNSYLVANIA, ASSIGNOR TO SUSQUEHANNA SILK MILLS, OF NEW YORK, N. Y., A CORPORATION OF NEW YORK.

BUNCH BUILDER.

Application filed October 3, 1921. Serial No. 505,062.

To all whom it may concern:

Be it known that I, ERNEST KORTEN, a citizen of the United States, residing at Sunbury, in the county of Northumberland and State of Pennsylvania, have invented certain new and useful Improvements in Bunch Builders, of which the following is a specification, reference being had therein to the accompanying drawings.

10 This invention relates to bunch builders, and the object of the invention is the provision of means for automatically controlling the width and depth of the bunch made on the winding spindle, or bobbin, by the bunch builder.

One of the essential operations in automatic weaving consists in replacing exhausted bobbins by full ones. This operation must be accomplished while the loom is running, 20 and without introducing any imperfections in the cloth. It is accomplished by a train of mechanism which functions and starts with the feeler of the loom. Various types of feelers have been brought out but I have 25 found the sliding type to be the most advantageous and will, therefore, confine my description to this one type.

When the bobbin has been exhausted, the feeler slides along the bare wood of the exhausted bobbin. This sliding motion is transmitted and sets into operation the replenishing mechanism. One or two revolutions of the loom may be required for this mechanism to complete the work of replacing the exhausted bobbin by a fresh one. During the revolutions filling must be supplied for the cloth. But since the operation of the feeler depends upon its sliding along the bare wood of the bobbin, it is obvious that the filling required for the extra revolutions cannot be stored on the same part of the bobbin as that used for the main supply of the thread. For, if any filling were on the quill in front of the feeler, this part could not slide along the wood, and set into operation the replenishing mechanism.

The extra filling must therefore be stored in a small bunch at the base of the bobbin out of reach of the feeler. Further, the yarn in this small bunch must be a continuation of the yarn of the bobbin proper. Again, the bunch must be wound tightly, otherwise layers of the yarn from the bunch would fall or slide down, become entangled with

the yarn of the bobbin proper and finally be carried into the goods to form weaving imperfections, besides prohibiting proper operation of the feeler.

It is the object of this invention to insure the winding of the bunch tightly and in such a fashion that it will not fall down or become entangled during any operation through which the filling carrier is put.

A further object is the provision of means for automatically controlling the width and depths of the bunch made on the winding spindle or bobbin by the bunch builder.

With the foregoing and other objects in view, my invention comprises certain novel combinations, constructions and arrangements of parts as will be hereinafter described, illustrated in the accompanying drawings, and more particularly pointed out in the appended claims.

In the drawings:

Figure 1 is a fragmentary view, in plan, of the winding machine, showing my device applied thereto.

Figure 2 is a sectional view, taken on line 2—2, Fig. 1, and looking in the direction of the arrows.

Figure 3 is a perspective view of my device.

Referring to the drawings by numerals: The thread guide 1 is provided with extension 2, which extension 2 is provided with an elongated slot 3 (Fig. 2) that registers with the elongated slot 4 in the controller arm 5; this construction is involved for the adaptation of my device to a "Universal" winding machine, such as shown in prior United States patents, issued to W. Marcroft, 1,084,459, issued January 13, 1914 and 940,489, 946,831, granted Nov. 16, 1909 and Jan. 18, 1910, respectively to S. W. Wardwell.

The lever 6 comprises a rod-like body 7 provided with a flattened end 8. In the flattened end 8 is longitudinally-extending slot 9. A bolt 10 pivotally connects the lever and broadened portion 11 of the controller arm 5. Slots 3, 4 and 9 register (Fig. 2) and in these slots is bolt 12 for fastening lever 6, controller arm 5 and thread guide 1 together, but permitting the lever 6 to swing upon its pivot, constituted by bolt 10, and impart a reciprocating movement to the thread guide 1.

On the traverse bar 13 is a block 14, which

block is held in an adjusted position on bar 13 by screw 15, inasmuch as screw 15 tightly engages, at its inner end, the bar 13. The collar-member 15^a is inserted in the outer end 5 of block 14, and the lock screw 16 is threaded into the bottom of block 14, with its inner end in the annular groove 16^a, on the collar-member 15^a. The lever 6 has its portion 10 aperture 7^a of the collar-member 15^a; this lever is, therefore, mounted to slide freely in the collar-member 15^a, carried by block 14.

The operation of the device is as follows: 15 The bobbin 17 is first placed on the winding spindle 18. The thread guide 1 is then moved into position in the same manner as heretofore in the case of the regular bunch builder. The yarn is then passed through guide 1 on the bunch builder, and then to 20 the thread guide 19 on the traverse bar 13. After the machine has been started, the traverse bar 13, which is known to have a reciprocating motion, imparts the same motion to the lever 6. The lever 6, which, as previously explained, pivots upon bolt 10, and being engaged by bolt 12 in turn imparts an identical, yet lesser, predetermined motion 25 to the thread guide 1. This motion causes the yarn to travel back and forth on the bobbin 17, thus making a bunch of a certain depth. As soon as the thread guide 1 is released through the operation of the mechanism within the bunch builder 20, the rounded body 7, of the lever 6, glides along 30 the collar 15^a, yet, remaining in contact with the same. When the yarn has been automatically released from the thread guide 1 on the bunch builder 20, it is then fed from the thread guide 19 on the traverse bar 13 35 and is thus traversed during the remainder of the winding of the yarn, which constitutes the bobbin proper.

The bunch builder 20 is usually constructed in various types. I use, in conjunction 45 with my improved device, a type such as hereinbefore specified, under the patents listed. The machines manufactured under the designated patents are generally known as "Universal winders."

50 The operation of quill-winding for my device consists of two parts. First, the small bunch is wound on the base of the bobbin, then the yarn of the bobbin proper is wound on the remainder. I am concerned only with the first part of the operation, that of constructing the bunch.

55 As hereinbefore stated, the bobbin 17 is first placed on the spindle 18. The thread guide 1 is placed in position by placing it to the left when it will catch, in the bunch builder 20, with a click. Then the yarn is threaded through thread guide 19, located on the traverse bar 13, then through the eye of the thread guide 1 of the bunch builder 60 20, whereupon, the machinery is started, 65

causing the revolution of the bobbin 17 and also causing the traverse bar to be moved forward and backward. In its motion, the traverse bar is constantly in contact with the small lever 21, at the left of the bunch 70 builder 20, hence, presses this small lever backward. A spring (not shown) on the inside of the bunch builder 20 keeps it in contact with the end of the traverse bar 13.

75 After the small lever 21 has been pushed backward a number of times, it is automatically drawn to the right and away from contact with the traverse bar 13. In the same movement, the thread guide 1 is also drawn to the right, due to the action of the 80 spring (not shown) on the inside of the bunch builder. In moving to the right, the thread guide 1 becomes unthreaded, and the yarn now passes directly through the thread guide 19 of the traverse bar 13 and is traversed back and forth, forming the bobbin proper. 85

90 During the interval that the thread is held stationary at the base of the bobbin, through the agency of the thread guide 1, a small, 95 loosely wound bunch will be formed by the rapid revolution of the bobbin. With my improved device, the operation of which has been hereinbefore specifically explained, during this same interval, the yarn is not held stationary, but is traversed back and forth on the base of the bobbin due to the sliding movement imparted to the thread guide 1 by the lever 6 and so forms a tightly wound 100 bunch. This advantage is accomplished by having the thread guide 1 movable and traversed back and forth by the lever 6 to which is imparted a reciprocating motion by the traverse bar 13.

105 While I have described the preferred embodiments of my invention, and have illustrated the same in the accompanying drawings, certain minor changes or alterations may appear to one skilled in the art to which this invention relates, during the extensive 110 manufacture of the same and I, therefore, reserve the right to make such alterations or changes as shall fairly fall within the scope of the appended claims.

115 What I claim is:

1. In a machine of the class described, the combination with a bunch builder provided with a thread guide, of a traverse bar associated with said bunch builder, bobbin-supporting means contiguous to said bunch builder, and means cooperating with said thread guide and said traverse bar whereby movement of the traverse bar will be imparted to the thread guide for affecting its position with respect to said bobbin-supporting means. 120

125 2. In a machine of the class described, the combination with a bunch builder provided with bobbin-supporting means and with a thread guide, a bobbin carried by said bob- 130

bin-supporting means, said thread guide positioned contiguous to said bobbin, a traverse bar contiguous to said bunch builder, and means cooperating with the thread guide 5 and the traverse bar for storing filling in distinct bunches upon the bobbin.

3. In a winding machine of the class described, the combination with a bunch builder having a thread guide, a winding 10 spindle and a traverse bar, of a bobbin supported by said winding spindle, and means cooperating with the thread guide and traverse bar for winding a small bunch at the base of the bobbin, substantially as described.

15 4. In a winding machine of the class described, the combination with a thread guide, winding spindle and traverse bar, of means cooperating with said thread guide and traverse bar for causing a filling or yarn 20 to be wound tightly in a small bunch at the base of the bobbin and a continuous winding of the yarn on the bobbin proper.

5. In a machine of the class described, the combination of a bunch builder provided 25 with a controller arm, a thread guide adjustably mounted on said controller arm, a traverse bar contiguous to said controller arm, a bobbin supported contiguous to said controller arm, and means connected to said 30 controller arm and actuated by said traverse bar for moving the thread guide by the action of the traverse bar.

6. In a machine of the class described, the combination of a bunch builder provided 35 with a controller arm, a thread guide on said controller arm, a traverse bar contiguous to said bunch builder, and a lever pivotally connected to said controller arm and cooperating with said traverse bar whereby 40 movement of the traverse bar will impart movement through the lever to said thread guide.

7. In a machine of the class described, the combination of a bunch builder provided 45 with a controller arm having an elongated slot and a broadened portion, a thread guide provided with an extension, said extension provided with a slot registering with the

slot of said controller arm, a traverse bar contiguous to said bunch builder, a block on 50 said traverse bar, a collar-member on said block, a lever engaging said collar-member and provided with a flattened end, said flattened end provided with a longitudinally-extending slot, a bolt extending through the flattened end of said lever onto the broadened portion of said controller arm pivotally mounting the lever upon said arm, and a bolt extending through the slots of said 55 flattened portion, broadened portion and extension slidably securing the same together.

8. In a machine of the class described, the combination of a swinging thread guide and a movable traverse bar, a lever connected to said thread guide and slidably 60 supported upon said traverse bar, and a bobbin supported between and contiguous to said thread guide and traverse bar.

9. In a machine of the class described, the combination of a movable thread guide, a 70 movable traverse bar associated with said thread guide, a lever pivotally and slidably connected to the thread guide and slidably associated with the traverse bar, said lever operated by the movement of the traverse 75 bar for adjusting the thread guide, means for supporting a bobbin contiguous to and cooperating with the thread guide.

10. In a machine of the class described, the combination of a bunch builder provided 80 with a slotted and broadened controller arm, a traverse bar contiguous to said bunch builder, a thread guide against the slotted portion of said controller arm, means in the slotted portion of said controller arm 85 and engaging the thread guide for adjustably securing the thread guide upon the controller arm, a lever pivotally secured to the broadened portion of the controller arm, means for slidably supporting the lever upon 90 the traverse bar, and a bobbin supported contiguous to the thread guide and the traverse bar.

In testimony whereof I hereunto affix my signature.

ERNEST KORTEN.
